UNITED STATES PATENT OFFICE.

FREDERICK B. WEISS, OF NEWARK, NEW JERSEY.

JEWELRY.

1,074,673.

Specification of Letters Patent.

Patented Oct. 7, 1913.

Application filed January 27, 1912. Serial No. 673,812.

To all whom it may concern:

Be it known that I, FREDERICK B. WEISS, citizen of the United States, residing at Newark, in the county of Essex and State of New Jersey, have invented certain new and useful Improvements in Jewelry; and I do hereby declare the following to be a full, clear, and exact description of the invention, such as will enable others skilled in the art 10 to which it appertains to make and use the same, reference being had to the accompanying drawings, and to characters of reference marked thereon, which form a part of this specification.

15 This invention relates, generally, to improvements in jewelry; and, the present invention has reference, more particularly to a novel setting or holding device for use with precious and semi-precious stones when 20 used as pendants or drops.

The present invention has for its principal objects to provide a neat, simple and secure means for securing the usual ornamental and metal setting or holding device 25 to the usually pointed or tapered end of a precious or semi-precious stone, with a view of obviating the drilling into the end of the stone, in a direction of the length of the stone, thereby avoiding largely the danger 30 of cracking or splitting the thin end-portion of the stone, and obviating the possibility of insecurely fastening the metal setting or holding device by means of a pin and cement upon the thin and longitudinally drilled 35 end-portion of the stone.

Other objects of this invention not at this time more particularly enumerated will be clearly understood from the following detailed description of the present invention.

40 With the various objects of the present invention in view, the said invention consists, primarily, in the novel setting or holding device for precious and semi-precious stones when used as pendants or drops; and, 45 the invention consists, furthermore, in the provision of a precious or semi-precious stone, in the form of a pendant or drop, provided near its pointed or tapered end-portion with a laterally drilled hole, and an ornamental metal setting adapted to be fitted 50 over the pointed and laterally drilled portion of the pendant or drop, and provided with means arranged within the said laterally drilled holes, whereby the stone is securely fastened in its supported relation

with the metal setting, and that without the use of cement, as is now the custom.

The invention is clearly illustrated in the accompanying drawings, in which:—

Figures 1 and 2 are two elevations of a 60 pendant or drop made according to and showing one embodiment of the principles of the present invention; and Fig. 3 is a transverse vertical section, taken on line 3—3 in said Fig. 2. Fig. 4 is a face view of 65 the stone, with the metal setting or holding device omitted from said view, and Fig. 5 is a part elevation and part vertical section of the stone, the said section being represented as being taken on line 5—5 in said Fig. 4. 70 Fig. 6 is a transverse vertical sectional representation of a metal setting and a stone, in the form of a pendant or drop, provided with a laterally drilled hole and illustrating in connection therewith a modified fastening 75 means, but still embodying the leading features of the present invention.

Similar characters of reference are employed in all of the above described views, to 80 indicate corresponding parts.

Referring now to the several figures of the drawings, the reference-character 1 indicates the usual precious or semi-precious stone, in the form of a pendant or drop, the surface-portions of which may be of any 85 suitable ornate configuration, as will be clearly understood. The said pendant or drop is provided at a suitable point, near the tapered or pointed end-portion 2 of the pendant or drop 1 with a receiving portion, 90 preferably in the form of a laterally extending hole, as 3, which is drilled or otherwise formed in the said pendant or drop 1.

Suitably mounted and fitted over the tapered or pointed end-portion 2 of the 95 pendant or drop 1 is an ornamental supporting or suspension device, made of metal or other suitable material in the form of a bell-shaped shell, as 4, with the upper end-portion of which may be connected, in any suitable manner, a ring, as 5, or other suitable means of suspension. One means of permanently securing the said shell 4 to the said pendant or drop 1 is shown more particularly in Figs. 2 and 3 of the drawings, said means consisting essentially of a pair of prong-like members or tongues 6 with which the said shell 4 is provided, the lower and free end-portions of said prong-like members or tongues 6 being angularly bent 100 105 110

in directions toward each other, to form suitable retaining or holding fingers or lugs 7, which are sprung from the opposite faces of the pendant or drop 1 into the said hole 3, in a manner clearly indicated in said Fig. 3 of the drawings. Thus, it will be seen, that the said shell or setting 4 for the pendant or drop 1 is easily and quickly mounted upon the pointed end-portion of the said pendant or drop, and is securely held in place against accidental displacement, and without drilling longitudinally in the thin or pointed end of the said pendant or drop, and without being compelled 15 to use cement, as heretofore.

In Fig. 6 of the drawings is shown a slightly modified means for securing the ornamental shell or setting upon the pointed end-portion of the pendant or drop. In this 20 construction, the pendant or drop 1 is likewise provided with a laterally extending hole, and the said setting or shell is provided in its opposite sides with suitably disposed holes or perforations, as 8, which 25 when the setting or shell is arranged upon the pointed end-portion of the pendant or drop, respectively register with the respective ends of the laterally extending hole 3 in the pendant or drop. A pin 9 of suitable length is thereupon passed through the registering holes 8 and 3, and the end-portions of the said pin 9 are then riveted down upon the surface-portions of the setting or shell, whereby the parts are securely mounted 35 in their assembled relation, as will be clearly evident.

I am fully aware that some changes may be made in the general arrangements and combination of the several parts, without departing from the scope of the present invention as set forth in the foregoing specification, and as defined in the clauses of the claims which are appended to the said specification. Hence, I do not limit my present

invention to the exact arrangements and 45 combinations of the said parts as described in the said specification, nor do I confine myself to the ornamental shape and the exact details of the construction of the said parts, as illustrated in the accompanying 50 drawings.

I claim:

1. In an ornament of the character specified, the combination with a pendant or drop formed with a pointed end-portion and 55 with a hole extending laterally across the pointed end-portion of said pendant or drop, of a bell-shaped ornamental shell mounted upon said pointed end-portion of the pendant or drop, and means connected with said shell and extending into retaining engagement with said laterally extending hole for 60 securing said shell in its mounted relation upon the pointed end-portion of the pendant or drop.

2. In an ornament of the character specified, the combination with a pendant or drop formed with a pointed end-portion and 70 with a hole extending laterally across the pointed end-portion of said pendant or drop, of a bell-shaped ornamental shell mounted upon said pointed end-portion of the pendant or drop, prong-like members connected with said shell, and fingers projecting from said prong-like members, said 75 fingers extending into retaining engagement with said laterally extending hole for securing said shell in its mounted relation upon the pointed end-portion of the pendant or drop.

In testimony, that I claim the invention set forth above I have hereunto set my hand this 25th day of January 1912.

FREDERICK B. WEISS.
